UNITED STATES PATENT OFFICE

HARLEY J. MEGLEY, OF CHICAGO, ILLINOIS

TYPE BAR MACHINE

Application filed June 24, 1926, Serial No. 118,176. Renewed February 21, 1930.

This invention relates to a machine for feeding type bars or slugs as they are delivered or supplied thereto, from the place of delivery or supply, past means for operating upon the slug and to a point of delivery or use and its objects are to provide a machine for accomplishing this automatically and in a continuous operation without injuring the type head of the slug or interrupting the feed through the machine by the operation or operations upon the slug and in which the machine can continue to operate without injury to any of the parts even in case of interruption in the advancement of the bars through the machine such as may result from irregularities in the bars, jamming or from any other cause.

The operation upon the slug in its course of travel from the point of supply to the point of delivery or use may groove, crimp, broach, saw, cut, or mill the slug or it may be any other forming, shaping, or finishing operation or combination thereof and the means for receiving the slug at the point of delivery may be corrugated paper for packing the slugs or it may be a galley, multigraph drum, segment, or any other suitable or preferred means.

In the particular embodiment of the invention shown the printing heads of the slugs are fed into the corrugations of strips or bands of corrugated packing material which is fed over the table of the machine to position the corrugations for successively receiving the slugs from the feeding mechanism, it being understood that the corrugated material is intended to be illustrative generally of any means of the character above set out for receiving the slugs from the feeding mechanism.

The bars to be finished and packed are placed on the table of the machine ahead of a pusher or feeder which feeds the bars successively into register with a channeled holder where the shaping, cutting or broaching operation is performed and into register with the grooves or the like in the packing material or holder. As the bars are registered with the channeled blocks and with the grooves in the packing material or holder, suitable

means receives the bars and feeds them into the channeled block where the desired operation or operations are performed and on through the channeled block to the corrugated paper, holder, or the like.

Where the bar is formed with grooves or other retention means in its character bearing head and with a weakened portion connecting the so-called gate to the head of the bar, a correspondingly grooved block may be provided for receiving and holding the grooved head of the slug in its movement to the packing material or holder and a knock-off device may be employed for severing the gate-portion from the slug head in the movement of the slug through the channeled block. Where the slug is not grooved or weakened in its formation, the present machine provides for grooving, shaping, broaching, crimping, cutting, or otherwise forming, shaping or finishing the head thereof and for cutting off the bar to the desired height, whether grooved or not.

The means for feeding the bars to the means which feeds them to the passage in the channeled block and through to the packing material or holder preferably exerts just enough tension to hold the bar tight without interfering with their feed to the passage or channel in line with the grooves in the packing material or holder. The means for feeding the slugs to the packing material may include a yieldable dog for yieldably taking over the end of the outer slug to feed it from the row of slugs to the packing material and for assuring proper feed of the slugs to the device and to the grooved or channeled block between the point of supply and the point of delivery. A yieldable knock-over device may be employed for knocking the outer slug laterally slightly so as to start it in its movement into the passage or channel of the block between the point of supply and the point of delivery and for assuring that the dog for feeding the slug laterally takes properly over the end of the slug.

The parts of the machine are positive in action, yet there is sufficient yieldability and over-riding action in the feed and other mechanisms, so that there will not be any

jamming or injury in the event of any impediment to movement in any parts.

The machine of my present invention is adapted to take any size type slug, such as 5 from five points to fourteen points or over and to form retention means thereon or to take the usual high slug and bring it to the desired height for a special machine, or both.

The length of the slugs may vary and I 10 provide adjustments for accommodating such variations and where the invention is employed for packing the slugs, the width of packing material may also vary. I also provide for setting the machine so that the travel 15 or distance of the packing material or holder per step may be varied for example, from .001 to .1 of an inch from its normal step.

The machine of my present invention is provided with means for indicating to the 20 operator or attendant the number of lines or slugs that have been packed or fed to the holder and for indicating the length of slug for which the mechanism which feeds the slugs laterally is set and I also provide for 25 cutting off the packing material into strips at any desired point, where the invention is employed in that connection.

The machine of my present invention is of 30 generally improved and simplified construction and it may be economically produced and operated with ease and facility.

The invention is illustrated in the accompanying drawings, in which:

Figure 1 is a top plan view of a machine 35 embodying the present invention;

Figure 2 is a side elevational view of the same;

Figure 30 is a fragmentary detail section of another embodiment; and

Figure 31 is a fragmentary perspective 120 view of the slug of Figure 30 showing the manner of broaching the rule thereon.

Referring to the drawings, Figures 1 to 20 inclusive, the present machine comprises in general the horizontal table 5 mounted upon a suitable base or legs 6 having supporting feet 7.

A reel 8 freely journaled at 9 in the framework or base 6 carries a roll of corrugated paper or board or other suitable material in 130

which the slugs or bars are packed. The packing material 12 is placed in roll form on the spindle 10 of the reel 8 and when the material of one roll is exhausted another roll

5 may be placed upon the reel. Packing material of different widths or slugs or bars of different lengths and with different numbers of corrugations per foot may be employed.

From the reel 8 the packing material 12 10 passes up around an idler roller 14 freely journaled at the front edge of one side of the table 5 and passing over the roller 14 it travels rearwardly over the table 5, being advanced rearwardly as the slugs are fed 15 thereto by feed mechanism designated generally at 15.

The slugs or bars are arranged upon the table 5 in upright position with their character bearing edges upwardly and in a row 20 18 (Fig. 1), parallel with the rearward path of travel of the paper 12. Pusher or feed means 20 feeds the entire row 18 of bars rearwardly toward a feed mechanism 22 and into successive registration with the channel 86 25 in the edge piece along the block 23. The feed mechanism 22 removes the bars from the row 18 one row at a time and feeds them laterally into and through the channel 86 and from the opposite end of the channel 86 30 into the successive channels in the paper 12.

The block 23 or the edge piece 85 thereof has ribs longitudinally along the sides of the channel 86 for supporting and guiding the grooved head of the slug. Where the head 35 of the slug is previously grooved the ribs may extend through the length of the channel 86, whereas where the slug is grooved in its movement through the channel 86, the ribs may be disposed only beyond the grooving 40 means in the path of movement of the slug from the point of supply to the point of delivery.

Where the slugs are delivered directly to the galley, multigraph drum, segment, or the like instead of to the packing material 12, the drum or other holder is mounted at the end of the block 23 where the packing material is now disposed and is adapted to have its grooves successively registered with the 50 channel 86 to receive the slugs therefrom.

The desired operation or combination of operations are performed upon the slug in its movement through the channel 86 without interrupting or interfering with the continuous operation of the machine.

Having now described in a general way the main parts of the machine, I shall now proceed to a detailed description of the various parts or mechanisms.

60 The particular slug shown in Figure 15 comprises the head 30 bearing the line of type or printing characters 31 and provided with longitudinal grooves 32 for mounting in the chases of the printing machine. The head 30 is connected by the weakened neck 33

with an integral base or gate 34 in the formation of the slug and the weakened neck 33 is thereafter severed to free the head 30 for use.

Where slugs of this sort are employed they 70 are arranged in upright position upon the table 5 in the row 18 ahead of the follower 20 with their character bearing edges facing upwardly.

The follower 20 is adjustably secured by 75 a thumbscrew 35 to one end of a bar 36 slidably mounted in a slot 37 in the table 5 parallel with the path of travel of the paper 12 thereover. The opposite sides of the bar 36 are grooved and the adjacent sides of the slot 37 have longitudinal tenons fitting in these 80 grooves and holding the bar against upward and downward displacement. The opening 40 through the follower 20 through which the screw 35 passes is elongated and opens 85 from one end of the follower, permitting adjustment of the position of the follower upon the bar 36 and convenient removal and replacement of the follower so that followers of different lengths for slugs of different 90 lengths may be conveniently interchanged.

For the purpose of advancing the follower 20 to feed the entire row 18 of slugs rearwardly toward the feed mechanism 22 the undersurface of the bar 36 has teeth or ridges 95 38 transversely across the same. These teeth 38 may be formed in a separate strip 39 secured to the undersurface of the bar 36 as shown in Figures 4 to 6 or they may, of course, be formed directly in the undersurface of the bar 36 itself.

Underlying and mounted for reciprocation beneath the bar 36 is a block 42. The block 42 is of generally channel cross section with out-turned margins 43 at the upper edges of its opposite sides. The out-turned margins 43 overhang strips 44 which may be removably secured to the table 5 and which support the block 42 for sliding movement beneath the bar 36.

110 Mounted in the channel portion of the block 42, between the opposite sides thereof, is a plate 45 having teeth 46 for engagement with the teeth 38 on the bar 36. The plate 45 is guided for up and down movement in the channel portion of the block and free thereof upon four pins 48 secured in the block 42 and engaging in suitable apertures in the plate 45. At its forward end the block 42 has a depending ear 49 to

115 which one end of an eccentric rod 50 is pivoted at 52. The opposite end of the eccentric rod 50 has an eccentric strap 53 surrounding an eccentric 54 on the shaft 55 so that as the shaft 55 is rotated the block 42 and plate 45 carried thereby will be reciprocated back and forth beneath the bar 36. The block 42 has an opening 56 for accommodating a coiled spring 58 which spring 58 is interposed between the dog plate 45 and 120 125 130

a plate member 60 resting upon the eccentric rod 50. In operation the shaft 55 preferably rotates in the direction indicated by the arrow in Figure 4 and reciprocates the block 42 through the rod 50. The forward movement of the rod 50 and block 42 are accompanied by an upward component or movement. This upward movement of the eccentric rod 50 yieldingly forces the plate or dog member 45 upwardly through the spring 58 and the teeth 46 thereof into engagement with the teeth 38 on the bar 36, the accompanying forward movement of the rod 50 and block 42 shifting or advancing the bar 36 rearwardly or to the left in Figure 4 through the engagement of the teeth of the dog member or plate 45 with the teeth of the bar 36. The rearward movement of the rod 50 is accompanied by a downward component of movement therein which releases the effort imparted upwardly upon the plate 45 through the spring 58 and permits the teeth 46 on the plate 45 to disengage and slide yieldingly beneath the teeth 38 without shifting the bar 36 with the rearward movement of the rod 50.

Thus the eccentric rod 50 continuously advances the row of slugs 18 rearwardly without releasing the advancing tension with the movement of the rod 50 in the opposite direction and the accompanying upward and downward movement in the rod 50 is utilized to create and release the advancing engagement between the plate 45 and the bar 36.

While the particular source of power may, of course, be varied, the source shown comprises an electric motor 62 mounted upon a shelf 63 at the bottom of the standards or legs 6. The motor shaft has a pulley 64 and suitably journaled in the upper part of the standard framework 6 is a shaft 65 having a relatively large pulley 66. A belt 68 transmitting about the pulleys 64 and 66 transmits the drive from the motor to the shaft 65. The shaft 65 bears a relatively small pinion 69 which meshes with a relatively large spur gear 70 on the shaft 72 and transmits the drive to the shaft 72 therethrough. The shaft 72 also bears a gear 73 which meshes with a gear 74 on the shaft 75 and transmits the drive to this shaft through these gears. The shaft 75 bears a worm gear 76 which meshes with a worm gear 78 on the shaft 55 and drives the same therethrough. The shaft 55 is shown as journaled in bearings 80 on the table 5.

The feed mechanism 22 comprises a bar 82 reciprocable at right angles to the direction of advancement of the slug row 18 in a guide 83 suitably secured upon the table 5. The guide 83 forms, in effect, a stop for the successive slugs 18. As the slug reaches the guide 83 the stop function thereof registers the grooved head of the slug with the

correspondingly ribbed groove 86 in the face or edge piece 85 along the rear edge of the block 23.

Pivoted at 90 upon a vertical pin 92 in the bar 82 and movable with the bar is a dog 93. The dog 93 has a nose which projects out through a slot 94 in the guide 83 and a spring 95 connected between the guide 83 and the dog 93 normally swings the dog into projected position from the guide as shown in Figure 10 and into engagement with a stop 96.

For the purpose of reciprocating the feed bar 82 an arm or lever 98 is pivoted at one end at 99 (Fig. 3) on the framework of the machine. The opposite end of this lever 98 is forked or bifurcated at 100 and engages over a horizontal pin 102 on a post 103. The post 103 is adjustably clamped in a longitudinal slot 104 in the bar 82, the clamping member 105 engaging the upper surface of the bar 82 and fitting in the enlarged slot 106 in the top wall of the guide 83 and the handle piece 108 for clamping the post to the bar being exposed above the guide 83. The post extends at its lower end as shown in Figure 11 through a similarly elongated slot 110 in the table 5.

To adjust the connection between the upper end of the arm 98 and the bar 82 all that is necessary is to loosen the handle 108 slightly slide the post 103 through the slot 104 in the desired direction and again tighten the handle 108. This adjustment is for accommodating type bars 18 of different lengths and for adjusting the point in the throw of the arm 98 at which the dog 93 is brought into action.

For the purpose of oscillating the arm 98 the shaft 72 is provided with a crank arm 115 and a link 116 pivotally connected at its opposite ends to this arm 115 and to the lever 98 imparts the throw of the crank 115 to the lever 98 to oscillate the same and reciprocate the feed bar 82. This crank connection between the shaft 72 and the lever 98 may obviously be adjustable if desired.

With the parts in the positions shown in Figure 8, the dog 93 is forced inwardly upon reciprocation of the feed bar 82 to the right by the type bar 18 adjacent the guide 83. As the dog 93 passes the right hand end of the adjacent slug 18 it is sprung out by the spring 95 into cooperation with the adjacent end of the slug 18 and upon reciprocation of the bar 82 in the opposite direction, that is, to the left, this engagement of the dog 93 with the adjacent end of the slug 18 takes up this slug and moves it laterally to the left (Fig. 8) into the ribbed groove 86 as shown in Figures 12 and 13. As the dog 93 reaches the limit of its movement to the left the slug fed thereby is completely out of the row 18 and the succeeding slug moves up into cooperation with the

guide 83 and into registration with the ribbed groove 86.

With the succeeding reciprocation of the feed bar 82 the succeeding slug 18 is shifted laterally into the grooved guide 23 and moves the preceding slug ahead of it out into the synchronously registered groove in the packing paper or material 12. At the limit of the movement of the dog 93 this time the 10 slug is again completely out of the row 18 so that the succeeding slug may be advanced to the guide 83 and the head of the first slug is removed from the gate or base portion and is completely out of the guide 23 and 15 packed in the corrugated paper or material 12.

In this embodiment of the invention the head of the slug being already grooved, the only operation necessary upon the slug while 20 it is in the channel 86 is to sever the gate of the slug from the character bearing head at the reduced connecting neck 33.

For this purpose there is fixed upon the shaft 55 beneath the guide 23 a pair of head 25 members 120 and extending longitudinally between and carried by these head members is a knock-off blade 122. This knock-off member 122 rotates with the shaft 55 and is timed to engage the gate 34 of the slug as 30 shown in Figures 13 and 14 when the slug is completely out of the row 18 and in the channel 86 between that row and the packing material and to break off or sever the gate or base from the character bearing head at 35 the weakened neck 33. To assure a clean break, a plate 125 of substantially the width of the guide 23 is hinged at 126 and has a turned up end 127 which engages the slug and as the knock-off member 122 comes into 40 engagement with the opposite side of the slug the plate 125 is lifted as shown in Figure 14 and provides in effect an abutment at the weakened neck of the slug for assuring a clean break there. The table or base plate 45 5 has an opening 128 through which the knock-off blade 122 operates to engage the base or gate of the slug. Upon being severed the gate or base 34 of the slug drops down upon and is discharged 50 by a chute 130 and the character bearing head 30 is fed on laterally into the aligned or registered channel in the packing material 12 or holder.

For the purpose of aligning and guiding 55 the row of slugs 18 on the left a guide 135 is secured at 136 upon the top of the table 5.

At the opposite ends of the slugs 18 and adjacent the feed means 22 is an adjustable spacer 140. This spacer comprises a bar 142 60 mounted upon the table 5 for adjustment in the direction of the lengths of the slugs 18 to vary the distance between the guide 135 and the opposing end of the spacer 140 to accommodate slugs of different lengths. The 65 spacer bar 142 may be guided by the coopera-

tion of the block 143 with the slot 144 therein and said bar 142 is adapted to be clamped fixedly in any desired position by the thumb-screw 145. The spacer 140 has a yieldable 70 follower plate or bar 148 yieldingly urged by springs 149 into cooperation with the adjacent ends of the slugs 18 to hold the slugs properly positioned between it and the guide 135. Set screws 150 may be provided for adjusting the yieldable follower plate 148 75 with respect to the spacer bar 142.

Pivoted on the slug cooperating end of the bar 142 upon a pivot 152 to swing in a horizontal plane is an arm 154. This arm 154 forms in effect a kick-over member which 80 engages the slug 18 adjacent the guide 83 as the slug is registered with the groove 86 in the guide 23 and kicks the slug laterally slightly as shown at 158 in Figure 8. This initially engages the head of the slug in the groove 86 and sets the opposite end of the slug in a little bit just preceding its lateral movement to the packing material which assures that the pivoted dog 93 will take over this end of the slug and shift the same laterally with its succeeding reciprocation.

For its kick-over action the arm 154 is provided with a reduced nose 160 (Fig. 8) which 85 engages only one slug adjacent the guide 83 at a time. The arm 154 is urged in a counter-clockwise direction (Fig. 8) by a coiled spring 162 so that as the head of the slug is freed by its registration with the slot 86 the arm 154 is swung in a counterclockwise 90 direction and by means of its nose 160 moves 100 the slug laterally slightly.

I wish to call attention at this point to the fact that whereas the follower 20 imparts a positive advancing movement to the row 105 of slugs 18, the actuating connection to this follower is yieldable to a degree so that should any of the slugs become jammed or fail to be moved away laterally the machine can continue to operate without injury to any of the parts. For example, the slug advancing dog 110 45 will simply slip or ride over the toothed bottom 38 of the bar 36 at said time. The other parts of the machine are also freed to continue operation without injury in such instances.

To permit insertion of the bar 82 into and removal from its guide 83 the open front side 115 of the guide 83 is provided with a removable cover plate 165 (Fig. 4) which may be provided with the opening through which the dog 93 is projected.

The corrugated packing material or the galley, multigraph drum, segment, or other holder or receiver as the case may be is operated or advanced synchronously with the follower 20 and reciprocating bar 82 to successively register the channels 132 with the channel 86 for the reception of the type slugs with each reciprocation of the bar 82 to the 125 left in Fig. 1.

Where the slug receiver is the packing paper or board 12 the mechanism 15 for advancing the corrugated paper or board 12 over the upper surface of the table 5 parallel 5 with the feed by the follower 20 and at right angles to the lateral feed by the reciprocating bar 82 and guide 83, operates synchronously with the follower 20 and reciprocating bar 82 to position one of the longitudinal depressions or valleys 132 in the corrugated paper in register with the slot 86 for the reception 10 of the type head 30 with each reciprocation of the bar 82 toward the paper 12. As the bar 82 moves to the right (Fig. 1) a corrugation or valley therein is moved into register with the opposite end of the slot 86 and remained 15 in registration therewith to receive the character bearing head of the type bar upon the movement of the bar 82 to the left (Fig. 1) whereupon the corrugated paper 12 is again advanced to position the succeeding vale or corrugation in register with the slot 86 to receive the succeeding type bar head. In this manner all that is required is to place the 20 type bars upon the table 5 between the follower 20 and the guide 83 and the follower 20 operates to successively register them with one end of the slot 86 while the feed mechanism 15 operates to synchronously register 25 the corrugations successively with the opposite end of the slot 86 and the feed mechanism 22 operates to feed the bars laterally to the guide 23, that is, into the slot 86 where the gate or base portions 34 are removed and to 30 feed the freed heads 30 into the corrugation of the packing material positioned to receive the same and the operation continues automatically so long as there are bars in the row 35 18 or until the desired number of bars have 40 been packed. The bars in the row 18 may be conveniently replenished from time to time by simply drawing the follower 20 forwardly and inserting additional bars ahead 45 of the same, the spring action in the feed means for the follower 20 permitting the forward withdrawal of the follower for this purpose.

The paper feed mechanism 15 comprises 50 a block 175 secured at 176 to one end of a bar 178 which underlies and moves beneath the table 5. The block 175 has a rib operating in a slot 180 formed in one side of the table 5 and extending rearwardly in the rearward extension 182 of the table 5 as shown 55 in Figure 1.

The block 175 is additionally guided upon the table 5 by a pair of parallel V ribs 183 (Fig. 17) which operate in V grooves 185 shown in Figure 1.

60 A trigger or arm 186 pivoted at 188 between a pair of flanges on the block 175 has a plate 189 secured thereto at 190. The plate 189 is disposed transversely, that is, parallel with the corrugations 132 and the plate end of the 65 arm 186 is swung downwardly by a spring

192 to engage the plate 190 in the corrugation at the end of the paper or board 12 so that the paper 12 will be drawn over the surface of the table 5 as the bar 178 and block 175 are advanced rearwardly.

70

The means for advancing the corrugated paper or board 12 is enclosed in a housing 200 disposed beneath the table 5 and provided with an upwardly opening pocket 202 beneath the slot 180. A toothed advancing bar 205 is mounted beneath the bar 178 in the longitudinal pocket 202. The bar 205 is normally urged to the right in Figure 16 by a coiled spring 208 which may be arranged in one end of the pocket 202 and confined beneath a ledge 209.

75

For the purpose of lifting the advancing bar 205 to frictionally engage the teeth thereof with the under surface of the bar 178 and for advancing the bar 178 rearwardly to feed the paper 12 rearwardly over the table 5, I extend the shaft 55 through the housing 200 and provide the shaft between the sides of the housing 200 as viewed in Figure 17 with a cam 212 fixed thereon for rotation therewith. Mounted in suitable angular recesses in the housing 200 and acting radially to the axis of the shaft 55 one upwardly and the other horizontally at substantially 90° therefrom are a pair of cam or wedge members 215 and 216. The cam 212 has two cam parts 218 and 219. The cam or wedge block 215 is provided with a roller 220 which co-operates with the cam part 218 and the cam or wedge block 216 is provided with a roller 221 which cooperates with the cam part 219. A block 225 interposed between the toothed bar 205 and the upper bevel or wedge-shaped end of the block 215 moves the bar 205 to the left (Fig. 16) when the block 215 is raised by the cam 218.

90

It is this movement of the bar 205 to the left which feeds or advances the packing paper or other material rearwardly over the table 5 and for the purpose of engaging the teeth 228 of the bar 205 with the under surface of the bar 178 at this time so that the movement of the bar 205 will shift the bar 178, a block 230 is interposed between the block 216 and the bar 205. The blocks 216 and 230 have cooperating bevel ends 232 so that as the block 216 is moved to the left by the cam 219 with the rotation of the shaft 55 the block 230 will be moved upwardly. A coiled spring 235 interposed between the bar 205 and the upper end of the block 230 yieldingly imparts this upward movement of the block 230 to the bar 205 and thereby engages the teeth 228 with the teeth 203 of the bar 178. These teeth are engaged as the block 215 is raised so that the shifting movement provided by the block 215 will be imparted to the bar 178 by the engagement of the teeth 228 with the under surface of the bar 178 at this time. At the same time the entire 105

95

100

105

110

115

120

125

130

actuating connection is again yieldable so that any possibility of damage or injury to the machine is avoided.

Obviously the under surface of the bar 178 5 may be provided with suitable transverse teeth for engagement by the teeth 228, if desired.

A stop 240 adjustable by means of a set screw 242 (Fig. 16) limits the throw of the 10 toothed bar 205. By adjusting the position of this stop and thereby the throw of the bar 205 by means of the screw 242 the amount that the corrugated paper or board 12 is advanced each time may be adjusted to suit 15 different numbers of corrugations per foot in the packing material.

The toothed bar 205 is provided with a longitudinal slot 245 (Fig. 16) through which a rod 246 passes. The rod or stem 246 is 20 adapted to be rotated from the side of the machine by means of a finger piece 250 as shown in Figures 1 and 18. This stem 246 passes through the slot 245 and within the slot it is scarfed at 252. With the stem 246 25 in the position shown in Figures 16 and 18, the toothed bar 205 is free to be moved upwardly by the blocks 216 and 230. By turning the stem 246 through substantially 180° from the side of the machine its full diameter is disposed vertically in the slot 245 and blocks the bar 205 against upward movement under the action of the blocks 216 and 230, the actuation of these blocks being taken up in the spring 235 at this time without moving or 30 shifting the bar 205. Obviously with the stem 246 set to permit advancement of the paper over the table, movement of the bar 205 to the left (Fig. 16) by the bar 215 advances the paper over the table and following this advancement the upward effort imposed by the blocks 216 is released and the coiled spring 208 returns the bar 205 for the 35 succeeding advancement without moving the bar 178 or paper in the opposite direction.

40 For the purpose of indicating the number of corrugations which have been advanced past the slot 86 and thereby the number of bars which have been packed one edge of the table 5 has a suitable scale 260 thereon 45 along which may be graduated in corrugations per foot and with variations to suit different packing paper.

For the purpose of setting the shifting or feed mechanism 22 for different lengths and 50 sizes of bars or slugs 18 the bar 82 is adjustable as already pointed out and for the purpose of conveniently indicating the adjustment a suitable scale 265 may be provided, as shown in Figure 9.

55 For the purpose of cutting the corrugated paper or packing material into the desired lengths or when the desired number of slugs have been packed I mount a guide bar 275 transversely across the path of travel of the 60 paper 12 on the table 5. A cutter block or

carriage 276 shown in Figure 20 is slidably mounted upon the bar 275. This carriage or block 276 has suitable depending jaws 278 in which a cutter 280 such as, for example, a fragment of a safety razor blade is adapted to 70 be clamped by a set screw 282. When the blade or cutter 280 becomes dull it may be conveniently replaced and by sliding the block 276 to the left (Figure 1) the cutter or blade 280 engages and severs the paper 12 directly beneath the bar 275. The strip of corrugated paper or packing material 12 rearwardly of the bar 275 is thereby freed from the roll of packing paper and with the slugs packed in the corrugations thereof is adapted 80 to be removed from the table of the machine and packed and delivered as desired.

A hold-down device 300 is provided just 85 ahead of the bar 275 for holding the paper down upon the table and preventing buckling thereof. A spacing bar 302 is arranged upon the table 5 for guiding one edge of the paper 12 and spacing bars 302 of different widths as for different widths of paper 12 90 may be readily interchangeable.

The follower 20 may have spaced points or 95 studs 305 engaging the slugs 18 as shown in Figure 1 to prevent buckling, also to prevent any irregularity in the slugs from interfering in any way with proper operation of the machine and to minimize friction and its retardation to the lateral sliding movement of the slugs from the row 18 as they are fed to the corrugated paper.

With the embodiment shown in Figure 21 100 the type bar or slug with its integral gate may be cast or formed of uniform cross section and without the longitudinal grooves 32 of Figure 15 or the reduced neck 33 of the same figure. In this case as the type slug or bar 315 passes through the guide block 23 it first engages a pair of cutters 316 which operate upon its upper end to form the longitudinal grooves 32'. After first passing the cutters 316 which form the grooves 32' the bar or slug 315 then encounters a third cutter 318 arranged toward the left of the guide block 23 as viewed in Figure 1 and this third cutter 318 cuts off the base or so-called gate of the slug on the line 320 of Figure 21 and frees the character bearing head 30' for packing in the corrugated paper and the use in the desired printing machine. The guide 23 may be grooved to receive the head of the slug 105 thus grooved and to hold it as it is moved past the cutter 318 and to the corrugated packing paper or board.

110 Two parallel rows 18 of type bars are shown upon the table 5. This may vary.

115 For the purpose of permitting different operations upon the slug in its movement from the point of supply to the point of delivery in the same machine I provide a pair of plates 400 and 402 interchangeable with the 120 125 130

block 23 and the flapper 125 of the preceding embodiment.

These plates 400 and 402 provide, as shown in Figures 23 to 26, ribbed channel 403 along 5 their meeting edges through which the type slug is moved as before. Spacers 405 mount the plates 400 and 402 upon the bed of the machine and space the same properly above the bed.

10 Underlying the opening 406 in the bed plate 408 is a filler plate 410 and journaled at their upper ends in the plates 400 and 402 and at their lower ends in the filler plate 410 are three shafts 412, 413 and 414. Each 15 of the shafts 412 and 413 carries a cutter 418, as shown in Figure 25. One of these cutters operates upon each side of the slug as the same enters the channel 403 and forms therein the grooves 420 and the re- 20 duced base 421.

The shaft 414 carries a cutter or saw 422 which operates upon the slug after it passes the cutter 418 and cuts the slug to the desired height. The shafts 412, 413 and 414 25 are adapted to have different cutters or saws mounted thereon and each shaft has a gauge block 425 upon its upper end for adjusting the height of the cutters in one thousandth of an inch.

30 Instead of cutting the slug to the desired height as shown in the previous embodiment a blade 430 may be provided, as shown in Figure 26. This blade 430 has a relatively sharp cutting edge 432 and is adapted 35 to be reciprocated over the bed of the machine and beneath the plates 400 and 402, as by means of a suitable eccentric connection with one of the drive shafts of the machine. For the purpose of permitting this 40 connection, (not shown), the bed of the machine is provided with a slot 435, as shown in Figure 1.

In Figure 27, I have shown a similar reciprocable cutter 430' for cutting the shank 440 of a T-shaped slug to the desired height. 45

This cutter 430' may be provided, as shown in Figures 28 and 29, with upstanding base protuberances for simultaneously crimping or waving the shank 440' of the slug longitudinally, as shown. The upstanding protuberances are indicated at 442 and are shown as mounted directly upon the cutter 443 and they wave or crimp the shank of the slug longitudinally, as shown in Figure 29, 50 simultaneously with cutting it to the desired height. To this end the adjacent edge of the blade 443' may be correspondingly waved and upon crimping the shank the slug 55 adapted to be cammed out to fill the slot 440 for endwise movement.

In Figure 30, I have shown a block 450 which is adapted to be mounted in the opening in the bed of the machine. This block 450 has a channel 451 for receiving the slug 60 452 which is shown as being without grooves

or the like. An underlying plate 453 fastened to the block 450 supports the bottom of the slug 452 and the printing base of the slug is provided with a rule 455, disposed up in an overlying block 456, which 70 is undercut horizontally at 457 to receive broaching bits 458.

The bits 458 are of the usual triangular cross-section and they are suitably connected 75 as through an eccentric mechanism with one of the drive shafts of the machine to be reciprocated thereby and broach the printing rule 455. For the purpose of permitting the eccentric connection, the bed plate is provided with suitable slots 460, as shown in Figure 1. The slug 452 with the rule 455 broached at 465 is shown fragmentarily in Figure 31.

In Figure 22, the multigraph drum 500, 80 shown in dotted lines, has chases 502 which are adapted to be successively registered with the channel 503 to receive the slugs therefrom.

I claim:—

1. In a machine of the class described, the 90 combination of a table for supporting a plurality of linotype slugs in a row, means for receiving the slugs, a reciprocable member, a yieldable dog pivoted thereto and adapted to contact with the ends of the slugs to move them in a vertical position from said row to said receiving means with the reciprocation of said member, a follower for feeding the slugs to said reciprocable member, and yieldable kick-over means for initiating the movement imparted to the slugs by said yieldable dog and for assuring cooperation of said dog with the slugs.

2. In a machine of the class described, the 100 combination of a table for supporting a plurality of articles, a support, means for receiving the articles, said support carrying packing material for accepting the articles from said receiving means, a reciprocable member for feeding the articles to said receiving means, a follower for feeding said articles to the reciprocable member, a member for advancing the packing material, a driving member, an actuating cam for said advancing member, a wedge connection between said cam and said advancing member, means for operating the reciprocable article feeding member including a connection between the driving member and the reciprocable article feeding member and an eccentric driving connection between the driving member and the follower. 110

3. In a machine of the class described, the 120 combination of means for supporting a printing slug having a printing head, means for receiving the head of the slug, means for feeding the slug to the receiving means, a grooved support having interlocking engagement with the head of the slug for supporting the slug in its movement to the receiving 125 130

means, said slug being in a vertical position and suspended from the grooved support for the slug head, and means adjacent said grooved support and in the path of movement 5 of the slug to the receiving means for operating upon the slug.

4. In a machine for reducing the height of type high line long printing slugs, each slug having a printing head and a base connected thereto by a weakened portion, the combination of means for supporting the type high printing slug, means for receiving the head of the slug and supporting the same thereby, means for feeding the slug to said receiving 10 means, and means in the path of movement imparted to the slug by said last means and operating between the base of the slug and the printing head for removing the base of the slug.

20 5. In a machine of the class described, the combination of means for supporting a row of line-long printing slugs, a reciprocable feed member for feeding the slugs from said row to means for receiving same, grooved 25 guide means engageable with the slugs for supporting same by suspension in their movement from the row to said receiving means, means adjacent said guide means for removing the base of the slug, a follower for advancing the slugs successively to said feed member, and means for advancing the receiving means synchronously with the operation of said feed means.

30 6. In combination, a supporting table for a row of printing slugs, a slug advancing member slidably mounted thereon and having a follower cooperable with the slugs, teeth on said advancing member, a driving shaft, a reciprocable block having eccentric 35 connection with said shaft, oscillatory means connecting the driving shaft and reciprocable block, a toothed advancing member yielding- 40 ly engageable with the teeth of said first member and reciprocable with said block for advancing said first member and the row of slugs, and means operable by said oscillatory 45 member for pressing the toothed advancing member toward the slug advancing member.

7. In combination, a support for a row of 50 type bars, a guide along one end of the bars, a spacer at the opposite ends of said bars and adjustable upon said support, a follower mounted upon said spacer and having yielding cooperation with the adjacent ends of 55 the bars, and a kick-over device pivoted upon said spacer.

8. In a packing machine means for supporting a strip of corrugated packing material, means for supporting articles in a row, 60 means for advancing the entire row of articles to position said articles successively in packing position, means for driving said advancing means, a yieldable connection between said driving and said advancing means permitting the driving means to override said

advancing means, means for imparting a step by step movement to the packing material to successively align the corrugations of said material with the packing position of said articles, and means for feeding the articles from 70 packing position to said corrugations.

9. In combination, a table for supporting packing material, means slidably mounted thereon for engaging and moving said material, a feed-bar for said slideable means, a 75 toothed advancing member for said feed-bar, cam means arranged to cause yielding engagement between said toothed member and said feed-bar, during the movement of said toothed member in one direction, mechanism 80 for reciprocating said toothed advancing member, and means for locking said toothed member against engagement with said feed-bar.

10. In combination, a feed-bar, a toothed advancing member for said bar, a cam-actuated wedge member for moving said advancing member in one direction, and a spring for moving said toothed member in the opposite direction, cam-controlled mechanism 90 for causing yielding engagement between said toothed member and said feeding bar during the first said movement and for releasing said engagement during movement in the opposite direction.

11. The method of finishing and packing grooved type bars having restricted gates attached thereto, which comprises, stacking the bars on their gates in vertical position with their type faces up, removing the bars 100 from the stack one at a time, suspending the bars from their grooves with their gates hanging free, severing the gates from the suspended bars, removing the bars and delivering them into a suitable packing.

12. In a machine for finishing and packing type bars that have been cast with grooves disposed on their sides adjacent the type face and with gates attached to the bar by a reduced portion, the combination of a table 110 for supporting said type bars in vertical position on said gates, means for moving the bars on said table, packing means adjacent to said table, grooved guides for engaging the grooves of said bars and suspending them while they are being transferred from said table to said packing means, means for moving said bars from said table through said guides to said packing means, and means in the path of movement of said bars for severing the gates therefrom.

13. In a machine for finishing and packing type bars that have been cast with grooves disposed on their sides adjacent the type face and with gates attached to the bar by a restricted portion, the combination of a table 125 for supporting said type bars in vertical position on said gates, means for moving the bars on said table, packing means adjacent to said table, means engaging the grooves of 130

- said bars for suspending them and guiding them from said table to said packing means, means for moving said bars from said table to said guiding means, and means including 5 a rotary hammer operating on the bars suspended in said guiding means for removing the gates from the bar said packing means receiving the bars after the gates have been removed therefrom.
- 10 14. The method of reducing the height of a type high printing slug to less than type high, said slug having a slug body, which comprises moving the slug in a given path and during its movement in said path bodily 15 severing the body of the slug within its height to divide said slug body into a printing head of less than type high and a removed base.
15. In a machine for reducing to less than type-high the height of a type-bar having a 20 printing head portion of a height less than type-high and provided with retention means for engagement in a chased carrier and a gate-like base portion, the combination of means for supporting the bar by said retention 25 means, means for moving the bar in a given path, and means for severing the bar within its height and below the retention means in the head to separate the gate-like base bodily from the printing head during 30 the movement of said bar in said path.
16. In a machine of the class described, in combination, means for supporting packing material, means for supporting a plurality of unitary type high printing slugs in a row, 35 said slugs being in length equal to the length of a plurality of type, means for advancing the row of slugs, means removing one at a time the forwardmost slugs and moving the same in a given path, means for severing the 40 base portion of the slugs when the latter occupy a position in said path, means for feeding the remaining portion of the slugs to said packing material, and means for advancing the packing material to successively receive 45 the last mentioned portions of the slugs.
17. A machine of the class described comprising, in combination, means for supporting a row of linotype slugs having grooved printing heads, means for moving the slugs 50 along an angular path in a horizontal plane, means disposed along one leg of said angular path for severing the base from the grooved head of each slug, and means for successively positioning packing means to receive the 55 printing heads.
18. A machine of the class described comprising, in combination, means for supporting a plurality of type high linotype slugs in a row, each having a base and a grooved printing head, means for intermittently advancing said row of slugs, means including a grooved support to receive the grooved head of each slug for removing the slugs, one at 60 a time, from the row, said last two mentioned means being alternately operable, 65 means to sever the base of each slug from the head thereof while it is in said grooved support, means to receive the severed head as it is moved from the grooved support by the next slug, and means for positioning the head receiving means and acting in timed relation with said row advancing means. 70
19. In a machine of the class described, means for supporting a plurality of type high linotype slugs in a row, means for removing a slug from the row and displacing it laterally thereof, said means including a movable member having a slug engaging element pivotally mounted thereon and movable to slug-engaging position when reciprocated in one direction and to a retracted position when reciprocated in the other direction, receiving means for the displaced slug provided with supporting means to engage and support the slug above the bottom thereof, said receiving means being of a length substantially equal to one slug, and means to advance the row of slugs. 75
20. In a machine of the class described, means for supporting a plurality of type high linotype slugs in a row, means for removing a slug from the row and displacing it laterally thereof, said means including a movable member having a slug-engaging element pivotally mounted thereon and movable to slug-engaging position when reciprocated in one direction and to a retracted position when reciprocated in the other direction, receiving means for the displaced slug provided with supporting means to engage and support the slug above the bottom thereof, 80 means operating on the slug while in the receiving means, a second receiving means for the slugs, means to advance the row of slugs, and means for advancing the second receiving means concomitantly with the row advancing means. 85
21. A machine of the class described comprising means for receiving a plurality of line long type-high printing slugs, each having a base and a printing head, means for reducing the height of the type-high slugs including mechanism for separating the printing head from the base, means to feed the slugs to the reducing means one at a time, 90 means to receive the severed bases, and movable means for receiving the printing heads, said last named means including parts advanced simultaneously with said feeding means. 100
22. A machine of the class described comprising means for receiving a plurality of line long type-high printing slugs, each having a base and a printing head, means for reducing the height of the type-high slugs including mechanism for separating the printing head from the base, means to feed the slugs to the reducing means one at a time, 105 means to receive the severed bases, movable means for receiving the printing heads, 110
- 115
- 120
- 125
- 130

5 said last named means having means for individually packing each printing head, and means for advancing the packing means in accordance with the number of printing heads received.

10 23. A machine of the class described comprising means for receiving a plurality of line long type-high printing slugs, each having a base and a printing head, each of said slugs being adapted to have a supporting groove formed therein near the printing head, means for reducing the height of the type-high slugs including mechanism for supporting each slug by the groove therein and separating the printing head from the base, means to feed the slugs to the reducing means one at a time, means to receive the severed bases, and movable means for receiving the printing heads, said last named means including parts advanced simultaneously with said feeding means.

15 24. A machine for handling line long printing slugs each having a base and a grooved printing head, means to support a row of said slugs including guide means for the row, movable means mounted thereon for engaging and moving said row of slugs between the guide means, a feed bar for said movable means, cooperating means on the support and movable means for guiding the latter, a toothed member for advancing the feed bar, and means for moving the toothed member into engagement with the feed bar and at the same time advancing the toothed member to move the feed bar and movable means along the cooperating guides.

20 25. The method of reducing the height of a type high printing slug to less than type high, said slug having a slug body, which comprises moving the slug by intermittent motion in a given path and during a period of intermission in the movement of the slug operating upon the slug to sever the body of the slug within its height whereby to divide 25 said slug body into a printing head of less than type high and a removed base.

25 26. In a machine of the class described the combination of a continuously operating means for moving a type high printing slug by intermittent motion in a given path, said slug having a slug body, and means operable with said continuously operating means for operating upon said slug across its width and during a period of intermission in the movement of the slug to sever the body of the slug within its height whereby to divide said slug body into a printing head of less than type high and a removed base.

30 27. In a machine of the class described the combination of continuously operating means for moving a printing slug by intermittent motion in a given path, said slug having a slug body, and means operable with said continuously operating means for operating upon said slug across its width and

35 during a period of intermission in the movement of the slug to prepare said slug for use in the chased carrier of a printing machine employing slugs which are less than type high.

40 In witness whereof I hereunto subscribe my name this 21st day of June, 1926.

HARLEY J. MEGLEY.
